HEATER APPARATUS

Lawrence C. Soule, Essex Fells, N. J., assignor, by
mesne assignments, to Carrier Corporation,
Newark, N. J., a corporation of Delaware

Application March 8, 1932, Serial No. 597,519

1 Claim. (Cl. 257—136)

This invention relates to heat exchange devices employed, more particularly, for heating or cooling air. The general type of heat exchanger to which this invention is directed usually comprises a series of tubes for the passage of steam or other temperature affecting medium, preferably provided with fins or plates to increase the radiating surface thereof, and one or more headers to which the tubes may be attached, and by which the steam or other medium may be introduced to and withdrawn from said tubes.

Heat exchange devices of this type are widely used in heating and air conditioning systems for buildings and other enclosures in which temperatures are usually controlled by varying the amount of steam or other conditioning medium admitted to the device. While such heat exchange device may be employed as a built-in component of a heating or air conditioning system, it is often desirable to have the devices constructed in the form of individual unitary heating and/or cooling units. Due to the great heat conductivity of the metal, and more particularly of the tubes, contained in such units, and because of sudden and wide changes in temperature to which the units are frequently exposed, and because the requirements of heating or air conditioning often demand the metal and tubes of the unit to be subjected to a wide range of temperatures, it follows that great strains and stresses are set up in the tubes and in the heaters to which they are attached, due to the consequent large expansion and contraction.

An object of this invention is to provide means whereby expansion and contraction of the tubes will be taken up without placing any undue strain on the headers or the connections between tubes and headers.

Another object of the invention is to provide means for spacing the tubes relatively close together, at the same time providing ample working space at the points of connection with the headers.

A further object of the invention is to provide means for positively draining any condensate formed in the tubes, without necessitating tilting the casing containing the tubes.

A feature of the invention resides in providing a tube with a bend therein adapted to compensate for heating and cooling stresses, as well as to provide for drainage, at one end of the tube. The structure enables the application of this feature to tubes of varying length by the same operation.

55 A further feature resides in reducing the size

of the tubes at their extremities, so that the radiating portion of the tubes may be spaced relatively close together and yet provide ample and accessible working space at the points of connection of the tubes and header.

Another feature is that the reduction of the size of the tubes at their extremities eliminates the necessity for providing individual orifice rings for the tubes, the smaller opening provided by the reduction in size of the tube serving as an orifice so that equal distribution of steam pressure to all the tubes will be assured.

Further objects and features of the invention, making for efficiency in operation and advantages and economy in design and assembly will be more apparent from the following description of an illustrative form of the invention to be read in connection with the accompanying drawings, in which:

Fig. 1 is a plan view of a unit incorporating the invention with some parts partly broken away.

Fig. 2 is a fragmentary view of a portion of a header used in connection with the unit illustrated in Fig. 1.

Fig. 3 is a fragmentary view, partly in section, of an assembly of tube connections at a header.

Fig. 4 is a side elevation of the unit shown in Fig. 1, and

Fig. 5 is a plan view of a section of radiating tubing of a type preferably employed.

Referring to the drawings, similar designations referring to similar parts, the heat exchange device illustrated comprises an inlet header 6 and an outlet header 7, connected by spaced radiating tubes 8, preferably of the type shown in Fig. 5. Such tubing consists of a tube 18 bearing fins or extended surface 19, so that greater radiation may be brought about by circulating a fluid, such as steam, hot water or cold water, through the tube. Steam or other medium entering header 6 from a supply pipe connected to the header at 9 will pass through the several tubes, into outlet header 7 and then leave the unit through a suitable discharge line at discharge connection 10. The headers may be constructed of any desired material and may be cast in one piece, or may be made of pressed metal. The connecting nipples 11 may be cast integrally with the headers or, as shown in Fig. 3, may otherwise be suitably connected thereto. Tubes 8 are contracted by swaging or they are otherwise suitably reduced in diameter at their extremities, as indicated at 12 in Figs. 1, 3 and 4. The nuts 13 are placed on the contracted or reduced ends of tubes 8, as shown in Fig. 3. The end of the tube is

then re-expanded to assume a frusto-conical shape, so that when a nut 13 is screwed on its corresponding nipple 11, the end of the tube will be firmly and securely pressed between the inner shoulder of the nut and the end of the nipple, as illustrated, thereby forming a vapor-tight joint. If desired, the tube could be welded to the header or could be fastened to a suitable nipple by joinder as disclosed, for example, in 10 Patent No. 1,770,852.

Each tube 8 is bent at 14, as illustrated in Fig. 4, a predetermined distance from one extremity thereof, and is again bent at 15. All the tubes are similarly bent at points 14 and 15 and the bends 15 are usually at predetermined identical distances from one end of the tube, although, if desired, the bends in different tubes may be variously positioned. As illustrated in Fig. 4, each point on the lower tube 8 may be considered in a plane 20 substantially parallel to a plane containing a corresponding point on the upper tube. Although the illustration shows two coils, one above the other, in a vertical plane, it is apparent that any number of coils may be similarly positioned 25 above one another in a vertical plane, and, as illustrated in Fig. 1, the number of such series of coils is limited only by the size of the unit or casing containing them. The bends at points 14 and 15 should not be sharp. In fact, it is 30 desirable to have sharp angle or short radius bends.

In shaping the tubes, the bends 14 and 15 will be positioned in each case at the same distance from one end of the tube and all tubes, regardless of their lengths, may, therefore, be subjected to the same bending operation, since the length of tubes for different size heaters may be increased merely by increasing the distance from the bend 15 to the inlet end of the tube at the 40 point it meets the connection at the inlet header. It will be noted from Fig. 4 that the bends 14 are placed relatively close to the discharge header 7. In practice, the bend is formed just as close to the discharge end of the tubes as is practicable 45 without interfering with the ability of the bends to absorb contraction and expansion. Thus, the discharge end portions of the tubes are relatively short, or the bends are formed a minimum distance from the discharge headers.

Bends 14 and 15 serve a double purpose. First, any expansion or contraction in the tubes will be taken up, due to this bent construction, without placing undue stress or strain on the headers or on the connections to the headers. Furthermore, 55 differences in temperature of individual tubes will be of no consequence, since each tube is free to expand and contract independently. Second, where the device is used for condensing vapor, such as steam, and is installed in a horizontal 60 position, some means must be provided for draining condensate to the discharge header; and the bends provided herein accomplish this result. Usually, such drainage has been effected by tilting the whole heater. However, by bending the 65 tubes, as illustrated, draining is automatically carried on in simple and trouble-proof fashion. It is obvious that the steam pressure will not be reduced substantially before it reaches bend 15 from inlet header 6 and that condensation, if 70 any, will take place beyond said point. Gravity itself would then be sufficient to bring about required drainage. However, the velocity of the flowing steam will aid gravitation in assuring complete drainage of condensate. Thus, the unit, 75 in flat position, will be self-draining. By flat

position is meant one in which vertical air flow is employed through the casing.

The bending of the tubes at two points measured from the discharge ends of the tubes also serves a double purpose. First, it makes possible the bending of all tubes for all sized exchangers upon one bending machine. As is apparent, if the distance from bend 15 to the discharge end of the tube is standard, then the total length of the tube may be varied to fit different sized exchangers by increasing the distance from bend 15 to the inlet end of the tube. Secondly, where the device is used for condensing steam, it is evident that the quantity of steam condensed will depend upon the heat load. Thus, when the steam is first turned on, excess quantities of condensate will be formed. It is not unusual in such cases for the heater to become water logged, i. e., the discharge headers and a portion of the tubes filled with condensate, due to the inability of the discharge line to carry off condensate at a sufficiently great rate. Obviously, any portion of the tubes which are water logged are "out of service" so far as condensing steam is concerned. In applicant's device, if the header 7 is completely filled, it is evident that only the short end portions, and a small part of the bent portions, of the tubes, will be out of service, while the remaining, and much greater part of the tubes is clear and useful.

By reducing the diameter of the tubes at 12, it is possible to space the radiating portion of the tubes closer together than would be the case if the tube ends were of the same diameter as the body portions of the tubes. As may be noted in Figs. 3 and 4, the spacing of the radiating portions of the tubes insures maximum radiation and permits interfitting of radiating surface, so that air passing through the heater will contact, to a maximum degree with the radiating surface. The reduction in tube end diameter, however, leaves ample working space at the ends of the tubes so that nuts 13, for example, may be easily reached for disassembly and repair, if necessary; and this spacing between ends is made possible, even though there is relatively no similar spacing between the radiating or body portions of the tubes themselves.

In heat exchange devices of this type, in which steam is employed, an orifice ring or similar device is usually placed in the ends of the tubes. This is for the purpose of providing a restricted opening so that steam at substantially uniform pressure will be fed to all tubes alike. However, by constricting the tubes, as applicant does when the tube ends are reduced in diameter, an orifice, for practical purposes, is provided for each tube. Thus, the construction of the tube itself, in addition to supplying advantages in assembly and enabling the packing of more radiating surface in a given casing also provides orifices for the tubes, so that the steam fed to each will be at substantially equal pressure.

The supply and discharge connections 9 and 10 are suitably fitted within support plates 16 which may be welded or otherwise fastened to headers 6 and 7 respectively. The plates 16 are provided with a number of holes 17 through which bolts or the like may be fitted to secure the device within a protective casing 20. The casing may be of any desired type, such as that shown in Fig. 1 for retaining a header and tubes in an encasement. Cover plates 21 are suitably fastened to support plate 16 and serve substantially to enclose the header, fittings and reduced por-

tions of tubes 8. As a result, air passing through the device will not be able to bypass any of the radiating surface, since the cover plates will force the air to pass through the extended radiating surface alone.

Supply and discharge connections or fittings 9 and 10, at opposite ends of the casing 20, are preferably located equidistant from the sides of the casing. This is an advantage in mounting the casing where supply and discharge pipes are in line and also enables the casing to give on both sides of the supply and discharge fittings if stresses should arise during assembly of the unit or while it is being installed. In practice, the offset, i. e., the distance between the center lines of the straight tube portions, is five inches, or a comparatively small percentage of the length of the casing. The width of the casing is, therefore, held within practical limits, even though applicant's double bend feature, and mode of assembly, is employed. Thus, the manner of assembling the casing, plus the character of the bent tubes make for flexibility instead of rigidity, so that breaks or distortion arising from stresses incident to installation or operation are substantially eliminated.

To prevent bypassing of air around the tubes, the casing 20 is preferably provided with baffles 22.

Since certain changes may be made in the above construction and different embodiments of the invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent of the United States, is:

In a heat exchanger a casing, headers mounted at opposite ends of said casing, a plurality of bent heat radiating tubes having reduced end portions joining said headers, said tubes being bent at two points relatively close together and at predetermined distances from one end of the tubes, said tubes being mounted on said headers so that the headers are at different elevations when the casing is in horizontal position, and plates on said casing for covering the headers and the reduced end portions of the tubes.

LAWRENCE C. SOULE.
